UNITED STATES PATENT OFFICE.

REAL FRENETTE, OF ROSEMOUNT, MONTREAL, QUEBEC, CANADA, ASSIGNOR OF ONE-HALF TO WILFRID LEMOINE, OF MONTREAL, CANADA.

STONECUTTING DEVICE.

Application filed March 19, 1927. Serial No. 176,737.

The present invention relates to improvements in stone cutting and dressing devices and has for its primary object to provide a device adapted to uniformly chisel or face 5 the surfaces of building stones and the like.

A further object of the invention is the provision of a stone cutting device which will cut the surface of the stone and eliminate the danger of chipping the corners.

10 A still further object of the invention is to provide a device of the above character designed to be conveniently handled by the workman and employed in association with a power driven hammer.

15 Another object of the invention is to provide a device of the above type having a resilient frame structure adapted to cushion the vibratory action of the hammer so as to reduce the vibration on the frame of

20 the device.

Still another object of the invention is the provision of a stone facing device which is relatively simple and durable of construction and which can be conveniently handled

25 by the stone cutter.

Other objects and advantages of the invention will become apparent as the description progresses.

In the accompanying drawing forming a 30 part of this specification and in which like reference characters are employed to designate corresponding parts throughout the same,

Figure 1 is a side elevational view of the 35 device in assembled position;

Figure 2 is a top plan view taken on the line 2—2 of Figure 1;

Figure 3 is a front elevational view of the hammer supporting frame;

40 Figure 4 is a similar view of the facing roller and roller supporting bracket; and

Figure 5 is an enlarged vertical transverse sectional view taken on the line 5—5 of Figure 4.

45 Referring to the drawing, wherein for the purpose of illustration is shown a preferred embodiment of the invention, the numeral 10 generally designates a roller bracket of inverted U-shaped formation embodying an upper horizontal cross bar 11 and parallel vertical side members 12. The centre of the horizontal cross bar 11 is formed with a central transverse recess in which is securely fixed a transversely extending 50 plunger rod 13. The plunger rod 13 is

formed with an annular collar 14 adjacent its lower end, this collar resting on the upper edge of the bracket cross bar 11 as shown to advantage in Figure 5. The side members 12 of the roller bracket 10 are 60 formed with transversely aligned bearing openings adjacent their lower ends, these openings being adapted to receive a transverse roller shaft 15.

65 Fixed on the intermediate portion of the shaft 15 and rotatable between the side members of the bracket 10 is a cylindrical roller 16 its outer periphery being cut to form a plurality of tapered uniform spikes 17 formed to provide relatively sharp points 70 at their outer ends. The spikes 17 are preferably of uniform formation and may vary in dimension for the particular application of the stone cutting device.

75 Mounted in association with the roller bracket 10 and normally extending in a horizontal position is an operating frame 18 formed of continuous rectangular structure having its longitudinal side bars bent in arcuate formation as indicated at 19. The intermediate side portions of the bars 19 are 80 formed with apertured bearing collars 20 through which the ends of the roller shaft 15 are projected. The extremities of the roller shafts are formed with transverse 85 openings in which are detachably fitted cotter pins 21 adapted to prevent displacement of the shaft. As shown to advantage in Figure 1, the end portions of the frame 18 are arranged in substantially horizontal alignment with the upper cross bar of the roller frame 10 and to which the ends of a longitudinal centre bar 22 are connected. The centre bar 22 is formed with a relatively 90 large central opening through which the collar 14 of the plunger may be vertically reciprocated. An essential feature of this structure is the provision of a centre bar formed of spring steel or other resilient material adapted to cushion the vibratory 95 movement of the bracket and roller during the operation of the dressing device.

100 Detachably connected with the roller bracket 10 and normally extending upwardly in vertical position is a hammer supporting bracket 23 of inverted U-shaped formation having its side legs 24 diverging toward a lower end and provided with horizontal apertured ears 25 at their lower extremities. The upper transverse extension 26 of the 110

bracket 23 is formed with a central opening the purpose of which will later appear.

The bracket 23 is connected to the roller bracket by means of a pair of side rods 27 formed with hooks 28' at their lower ends engageable with the end portions of the roller bracket cross bar and extending vertically upward in diverging positions. The upper end portions of the side rods 27 are 10 exteriorly screw threaded so as to receive thereon adjusting nuts 28. Helical compression springs 29 are positioned about the side rods 27 between the adjusting screws 28 and the ears 25 of the bracket 23 so as to normally urge the bracket downwardly towards the roller bracket.

In use, a conventional type of power operated hammer indicated at 30 is positioned vertically between the upper cross bar of the bracket 23 and the longitudinal centre bar 22 of the frame. This hammer may be pneumatically or electrically driven to reciprocally drive a hammer. The lower end of the hammer body 30 is formed with a vertical recess into which projects the plunger 13 of the roller bracket, the plunger being arranged in vertical alinement with the reciprocating hammer and engageable therewith in the lowermost position of the hammer. Thus, when the hammer is operated, the hammer head will operate against the plunger and consequently, against the roller bracket 10 and spike roller 16. In this manner, the spike roller will perforate the face of the stones for the purpose of dressing the same.

Due to the arrangement of the guide frame, the reciprocating impulse will not be directly transmitted to the frame so that the operator can hold the hammer in accurate position and will not receive the complete vibration of the power hammer. The upper hammer bracket 23 is arranged to resiliently maintain the power hammer 30 in operative position on the plunger 13.

During the operation of the hammer, roller spikes 17 will be uniformly driven into the surface of the stone and due to the compact uniform arrangement to obviate chipping the edges of the stone. It will also be noted, that the device can be conveniently disassembled for shipping or storage purposes.

It is to be understood that the form of my invention herewith shown and described is to be taken as the preferred example of the same, and that various changes as to the shape, size and arrangement of parts may be 60 resorted to without departing from the spirit of the invention or the scope of the subjoined claims.

Having thus described my invention, I claim:

65 1. A device of the character described

comprising a roller bracket, a spiked roller carried by the bracket, means for resiliently supporting a power hammer in operative association with the roller bracket, and a guide frame resiliently mounted on the 70 roller bracket.

2. A device of the character described comprising a roller bracket, a spiked roller journaled in the bracket, an extension formed on the centre of the bracket, mechanism for resiliently supporting a power hammer in association with the bracket projection formed thereon, and a hammer guide frame resiliently associated with the wheel bracket. 80

3. A device of the character described comprising a U-shaped roller bracket, a spiked dressing roller journaled in the bracket, a rod secured in the upper transverse portion of the bracket, a hammer retaining bracket resiliently associated with the roller bracket and adapted to maintain a power hammer in operative association with the roller frame and rod, a U-shaped frame including a resilient central bar connected with the roller bracket for convenient operation of the roller. 90

4. A device of the character described comprising a U-shaped roller bracket, a spiked roller journaled on a transverse shaft extending through the roller bracket, a plunger rod fixed in the upper cross bar of the roller bracket, a pair of rods detachably connected with the roller bracket, a hammer supporting bracket slidably associated with the said rods and resiliently urged to a downward position, and a guide member including a rectangular frame journaled on the roller shaft extensions and having a resilient longitudinal centre bar connected 100 at its ends. 105

5. A device of the character described comprising a roller supporting bracket, a plunger rod secured in the bracket and extending vertically upward therefrom, a spiked roller journaled in the lower portion of the bracket, a guide frame resiliently connected with the roller bracket, and a hammer securing frame detachably and resiliently connected to the roller bracket. 110

6. A stone dressing device comprising a roller supporting bracket, a plunger rod fixed in the bracket, a roller formed with tapered spikes journaled in the lower portion of the roller bracket, a roller guide frame resiliently mounted on the roller bracket, and a hammer supporting bracket resiliently connected with the roller bracket adapted to firmly secure a power hammer in association with the roller bracket and the 120 plunger rod. 125

In witness whereof I have hereunto set my hand.

REAL FRENETTE.
